UNITED STATES PATENT OFFICE.

CHANDLER L. PARKER, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TRUING DEVICE FOR ROLLS OF BUFFING-MACHINES.

1,272,511.

Specification of Letters Patent. Patented July 16, 1918.

Application filed December 30, 1913. Serial No. 309,579.

To all whom it may concern:

Be it known that I, CHANDLER L. PARKER, a citizen of the United States, residing at Lynn, in the county of Essex and State of Massachusetts, have invented certain Improvements in Truing Devices for Rolls of Buffing Machines, of which the following description, in connection with the accompanying drawings, is a specification, like reference characters on the drawings indicating like parts in the several figures.

This invention relates to buffing machines and is illustrated in connection with a machine for buffing the bottoms of boots and shoes.

Machines for buffing boots and shoes commonly comprise two buffing rolls mounted upon a rotary shaft, each roll having a hub about which is wound a comparatively thick body of felt; and in use the roll is covered by a piece of sandpaper which is wound about the felt backing and fastened in some suitable manner.

There are various types of these rolls which differ principally in the manner in which the sandpaper is fastened, but the present invention is not concerned with any particular type.

Such rolls rapidly get out of true, and heretofore it has been customary in truing them to employ a flat strip of wood to which is fastened a piece of sandpaper. To true up a roll the operator removes the sandpaper cover, starts the machine, and applies to the felt the tool which has been described above. Such a procedure is at best a crude one and except when performed by a skilful artisan produces undesirable results. The object of the present invention is to do away with this hand method and to provide a truing device which shall obviate the former necessity for skill and at the same time perform the truing operation with precision and despatch.

One feature of the invention comprises a buffing machine having a plurality of buffing rolls in combination with a holder mounted on the frame of the machine and a truing tool carried by said holder and arranged to be moved with said holder to present said tool to a selected roll. In the illustrated machine the holder is movable angularly and longitudinally with respect to a rod or track which is parallel to the roll

shaft so that the tool may readily be presented to the selected roll.

This and other features of the invention, including certain details of construction and combinations of parts will be set forth in connection with an illustrative machine and pointed out in the appended claims.

Referring now to the accompanying drawing, the figure shows in perspective a portion of a machine for buffing boots and shoes in which the present invention is embodied.

The roll shaft of the machine is indicated at 1, and upon it are mounted two buffing rolls 2 each having a thick layer of felt about which, when the machine is in use, is wound a cover of sandpaper. The roll shaft may be rotated in any suitable manner, as, for example, by the usual belt and pulley from a countershaft; but inasmuch as the particular manner in which the sandpaper is fastened about the rolls and the particular manner in which the roll shaft is driven are immaterial so far as the present invention is concerned, these details have not been shown.

Mounted in the sides of the frame of the machine and extending parallel to the roll shaft 1 is a rod or track 3; and slidably and rotatably mounted upon said rod is a tool holder 4, said holder having hubs 11 through which said rod passes so that the holder is in effect pivoted to the frame of the machine and may be swung into and out of operative position. The forward portion of the holder 4 is formed as a yoke between the arms of which is held a second rod 6 upon which is mounted a truing tool 5 herein shown as half-round in cross section and covered on its curved underside with sandpaper 13. Fast to the upper flat face of the tool 5 are two hangers 15, 17 having eyes through which passes the rod 6 so that the tool may be moved both angularly about said rod and lengthwise thereof, said latter movement being possible by reason of the fact that the distance between the outside faces of the two hangers is less than the distance between the inner faces of the arms of the yoke.

The hanger 17 is formed with a track 7 into which extends a roll 8, said roll being carried by a bracket which is part of one arm of the yoke of the holder 4; and this cam track is so shaped that when the opera-

tor grasps the handle 9 and swings it up and down, the tool 5 is caused to reciprocate slightly in a direction parallel to the axis of the buffing roll 2.

- 5 While the buffing machine is being used the tool holder 4 is swung back out of the way, and the usual hinged cover 19 of the exhaust conduit is swung forward so that its front edge is close to the surface of the buffing rolls and a strong draft is secured for carrying away the dust. When it is desired to true the rolls the sandpaper covers thereof are removed to expose the felt backing, the cover 19 is swung back, after which 15 the tool holder 4 is swung forward into the position shown with the tool 5 in contact with one or the other of the buffing rolls, and the handle 9 manipulated to rock and reciprocate said tool.
- 20 In order to limit the downward movement of the holder 4 an adjusting screw 10 is threaded through a bar of said holder and contacts with the upper wall of the exhaust conduit in the rear of the hinged cover 19.
- 25 The rod 3, it should be understood, extends the whole width of the machine so that the holder 4 may be moved along it into position to coöperate with either roll 2 as may be desired. In order to permit the whole truing 30 device to be removed readily from one machine and attached to another the sides of the frame of the machine are provided with sockets one of which is adapted to receive a reduced end portion of the rod 3 and the other to receive a locking bolt 27 which is 35 slidable in a socket in the end of said rod and is continuously urged outwardly by a spring 18. A pin 21 fast to said locking bolt 27 furnishes means for withdrawing said 40 bolt and coöperates with a slot 22 to form a bayonet joint whereby said bolt may be held in retracted position when it is desired to remove the truing device.

Although the invention has been set forth 45 in connection with a particular machine it should be understood that the invention is not limited in the scope of its application to the particular machine shown and described.

Having thus described my invention, what 50 I claim as new and desire to secure by Letters Patent of the United States is:

1. The combination with a buffing machine having a plurality of buffing rolls arranged with their axes in alinement, of a 55 track on the frame of the machine extending parallel to said axes, a holder slidable on said track whereby it may be moved into position opposite a selected roll, and angularly movable in a path at right angles to said axes, and a truing tool carried by said holder.

2. The combination with a buffing machine having a plurality of buffing rolls arranged with their axes in alinement, of a track on 60 the frame of the machine extending parallel

to said axes, a holder slidable on said track whereby it may be moved into position opposite a selected roll, and angularly movable in a path at right angles to said axes, a truing tool carried by said holder, and means 70 for rocking and reciprocating said tool.

3. The combination with a buffing machine having a plurality of buffing rolls arranged with their axes in alinement, of a rod supported by the frame of the machine 75 and extending parallel to the axes of the buffing rolls, a holder mounted for angular movement about the rod toward and from the rolls and for movement longitudinally of the rod to bring the holder opposite a 80 selected roll, and a truing tool carried by said holder.

4. The combination with a buffing machine having a plurality of buffing rolls arranged with their axes in alinement, of a 85 rod supported by the frame of the machine and extending parallel to the axes of the buffing rolls, a holder mounted for angular movement about the rod toward and from the rolls and for movement longitudinally 90 of the rod to bring the holder opposite a selected roll, a truing tool carried by said holder, and means for limiting the angular movement of the holder toward the rolls.

5. The combination with a buffing machine 95 having an abrading roll and an exhaust conduit for carrying away the dust generated by said roll, of a truing device comprising a holder pivoted to the frame of the machine and arranged to be swung 100 into and out of operative position, a tool carried by said holder, and a stop also carried by said holder and arranged to contact with a wall of the exhaust conduit to arrest the swinging movement of the holder toward the 105 roll.

6. The combination with a buffing machine having a buffing roll, of a truing device comprising a holder carried by the frame of the machine, a truing tool carried by the holder, 110 and manually operated means for rocking said tool while maintaining it in contact with said roll.

7. The combination with a buffing machine having a buffing roll, of a truing device comprising a holder carried by the frame of the machine, a truing tool carried by the holder, and manually operated means for rocking and reciprocating said tool.

8. The combination with a buffing machine 120 having a plurality of buffing rolls arranged with their axes in alinement, of a track carried by the frame of the machine extending parallel to said axes, a holder slidable on said track whereby it may be moved into 125 position opposite a selected roll and angularly movable in a path at right angles to said axes, a truing tool carried by said holder, and means for limiting the approach of the tool to the selected roll.

9. The combination with a machine having a plurality of rolls arranged with their axes in alinement, of a truing tool, and connections between the tool and the frame of
5 the machine such that the tool may be presented to a selected roll.

In testimony whereof I have signed my

name to this specification in the presence of two subscribing witnesses.
